DESIGN.

J. EICHEL.

CANE HEAD.

~~No.~~ 18,540.

Patented Aug. 21, 1888.

UNITED STATES PATENT OFFICE.

JACOB EICHEL, OF EVANSVILLE, INDIANA.

DESIGN FOR A CANE-HEAD.

SPECIFICATION forming part of Design No. 18,540, dated August 21, 1888.

Application filed March 20, 1888. Serial No. 267,907. Term of patent 7 years.

To all whom it may concern:
Be it known that I, JACOB EICHEL, a citizen of the United States, residing in the city of Evansville, in the county of Vanderburgh and State of Indiana, have invented and produced a new and original Design for Cane-Heads, of which the following is a specification, reference being had to the accompanying photograph, forming part thereof, and showing my design in side elevation.

My design consists of an ordinary cane-stick having at one end a "rooster's head," A, bill B, imitation eyes C, set in said head in their natural position, said head being provided with a comb, D, and gills E, the head of said rooster being suitably carved to represent feathers, *a*, in a clipped condition.

The essential feature of my invention is the head of a fighting cock trimmed for a fight—that is to say, with its head-feathers, the gills,

and the comb trimmed down as in preparing a cock for a fight, the general expression of the head being that of a fighting cock ready for an affray or exultant after a victory, as distinguished from a cowardly or defeated expression; or, in other words, the essential feature of my design is a rooster-head rampant.

Having described my design, what I claim, and desire to secure by Letters Patent, is—

The herein-described design for cane-heads, the same consisting of a stick having mounted thereon a carved rooster-head of the fighting-cock species having its comb and feathers clipped, substantially as shown and described.

JACOB EICHEL.
